United States Patent Office.

SAMUEL KELLETT, OF SAN FRANCISCO, CALIFORNIA.

Design No. 4,966, dated May 30, 1871.

DESIGN FOR CENTER-PIECE.

The Schedule referred to in these Letters Patent and making part of the same.

To all whom it may concern:

Be it known that I, SAMUEL KELLETT, of San Francisco, in the county of San Francisco and State of California, have invented or produced a new Design for a Center-Piece in alto-relievo; and I do hereby declare that the following is a full and exact description of the same, reference being had to the accompanying drawing and to the letters of reference marked thereon.

The drawing, consisting of only one figure, represents my new design for center-pieces.

This design consists of a rosette, A, with radial arms of an architectural figure, *a*, upon a wheel with raised or convexed edge, *b*.

Radial arms of combined architectural figures *c* are attached to this wheel and extend to the edge of the design, passing over a reeded molding, *d*, having a ozenge edge, *e*.

Two bands, *f*, pass over the reeded molding between the arms, crossing each other in a diagonal manner, as shown.

Between each series of the outer radial arms is placed a bouquet, composed of daisies and leaves *g*, with heads composed of shell-work and scroll-work *h*.

Having thus described my invention or production, What I claim, and desire to secure by Letters Patent, is—

The design for a center-piece, as described.

In witness whereof I have hereunto set my hand and seal.

SAML. KELLETT. [L. S.]
